HAROLD STEPHEN MULHOLLEN, OF LOS ANGELES, CALIFORNIA

TRAFFIC ALARM FOR HIGHWAYS

Application filed July 6, 1931. Serial No. 548,811.

This invention relates to a vehicular highway traffic signal to produce an audible alarm. It is adapted for installation across the highway to signal approach of a vehicle 5 to zones or intersections, such that precaution may be observed by the driver or those in the vicinity using the highway. Heretofore, visible and/or audible alarms have been used and proposed for this purpose. The 10 alarms involve complex apparatus subject to disorder and having sensitive parts requiring almost constant supervision and frequent servicing.

The present invention has for its primary 15 object the provision of a rattle ranging transversely of the road with actuating sections disposed in the surface of the roadway to be operated by vehicles passing thereover.

These objects together with other objects 20 and corresponding accomplishments are obtained by means of the embodiment of my invention illustrated in the accompanying drawing, in which:

Fig. 1 is a diagrammatic view in plan of a 25 highway and intersecting railway with two signal units installed on the highway adjacent the railway; Fig. 2 is a perspective view in vertical section through one species of the invention as installed; Figs. 3 to 6 are 30 vertical sections of other species.

Referring more particularly to Fig. 1, a highway is denoted by A and an intersecting railway by B. It is assumed that the traffic moves forward on the right hand side of the 35 highway. C are signal units ranging from the center line of the highway to the edges and disposed at such distances from the intersection as to give warning of a dangerous crossing in sufficient time for the driver 40 of a vehicle to slow down or stop. These units are rattlers.

Referring to Fig. 2, a pit 7 is formed in the highway transverse thereof and installed therein is a rattle box 8 of channel form. 45 The upstanding legs of the channel have shoulders 9. In the box are a series of lids or plates 10 of such width that their edges may strike the shoulders 9. A fulcrum rocker 10 extends from the bottom of the lid 50 and rests on the web of channel 8. The

height of the rocker is such that the lid may only abut one of the shoulders, it being unstable and constituting a percussor to coact with the anvils formed by shoulders 9. Upon a vehicle wheel passing thereover, the 55 unbalanced lid is rocked by reason of the wheels passing thereover from side to side which cause it to vibrate and strike the shoulders with a percussive effect and produce a rattling or drumming noise. Obviously, the upper surface of the lid is substantially flush with the highway surface and the box 8 and rattler 10 are preferably of metal to produce sufficient noise. The floor plates 10 produce in effect a continuous highway surface. 60

Referring to Fig. 3, the box 11 is formed with overhanging shoulders 12 constituting anvils. Ears 13 are provided on the bottom of the box. The floor lids 14 have shoulders 15 constituting percussion members to coact with shoulders 12 in producing percussion and retaining the lids in place. Each of the lids has an ear 16 for pivotal attachment by a pin 17 to a corresponding ear in the box. 70 The operation is obvious. 75

Referring to Fig. 4, box 18 has overhanging shoulders, and its bottom has a fulcrum projection 19. Resting upon fulcrum 19 so as to seesaw is a percussive plate 20 having 80 flanges to cooperate with the anvil shoulders on the box.

Fig. 5 shows a box 21 preferably with a stable cover 22 forming an anvil. The cover has an ear 23 depending therefrom and holes 24 spaced from the ears. A percussor 25 has an elbow 26 at one end and a weight 27 at the other end. The percussor is pivotally mounted on ear 23 so that elbow 26 normally projects above the cover. A compression spring 85 28 aids the counterbalance weight 27 in normally maintaining the elbow projected. Wheels of a vehicle engaging the tip of percussor 25 will depress the latter and weight 27 on being restored to normal position will 90 strike the bottom of the box. The weight may also strike the cover on depression of the percussor. 95

In Fig. 6, an anvil box 29 is provided with a cover 30 having holes 31. In these holes 100

are loosely mounted percussor bolts 32 with heads above the cover. A vehicle wheel passing thereover will disturb the bolts causing them to rattle.

5 Although I have shown several species, other variations may be resorted to as found expedient.

What I claim is:

1. In combination with a vehicular highway having a pit ranging transversely thereof, a rattle channel frame disposed in said pit and open at the top, a lid plate substantially flush with the highway surface loosely mounted thereon and rockably supported, 10 coating shoulders on said lid and frame providing percussion surfaces and limiting the rocking of said plate whereby a vehicle wheel passing thereover will rock said plate and produce an audible drumming.
2. In combination with a vehicular highway having a pit ranging transversely thereof, a rattle channel frame disposed in said pit and open at the top, a lid plate substantially flush with the highway surface fully 15 crumpled intermediate its edges on said frame, coating shoulders at the edges of said frame and lid providing percussion surfaces and limiting the rocking of said plate whereby a vehicle wheel passing thereover will rock 20 said plate and produce an audible drumming.
3. In combination with a vehicular highway having a pit ranging transversely thereof, a rattle channel frame disposed in said pit and open at the top, said frame having shoulders at the margin of its opening, a lid plate substantially flush with the highway surface and having shoulders at its edges coating 25 with the first mentioned shoulders to provide percussion surfaces, a fulcrum projection intermediate the bottom of said frame and said plate to support said plate in unstable rocking position in said frame whereby a vehicle 30 passing thereover will rock said plate and produce an audible drumming.
4. In combination with a vehicular highway, an isolated rattle device disposed in the highway surface and ranging transversely 40 across a traffic lane thereof, said rattle comprising an anvil secured in position on said highway and a percussor loosely mounted on 45 said anvil.
5. In combination with a vehicular highway, an isolated rattle device disposed in the highway surface and ranging transversely 50 across a traffic lane, said rattle comprising anvil means secured in position on said highway, and a rocker percussor fulcrumed intermediate its side edges on said means and 55 loosely secured thereto.

60 In witness that I claim the foregoing I have hereunto subscribed my name this 29th day of June, 1931.

HAROLD STEPHEN MULHOLLEN.
